(57) **CLAIM**

The ornamental design for a handheld x-ray analyzer, as shown and described.

DESCRIPTION

FIG. 1 is a perspective view of a handheld x-ray analyzer comprising the new design;

FIG. 2 is a left side elevational view thereof;

FIG. 3 is a right side elevational view thereof;

FIG. 4 is a front view thereof;

FIG. 5 is a rear view thereof;

FIG. 6 is a top view thereof; and,

FIG. 7 is a bottom view thereof.

The broken lines in the drawing views are included for the purpose of illustrating portions of the handheld x-ray analyzer that form no part of the claimed design.
